G. F. NUTTING,
OILING SYSTEM FOR ENGINES.
APPLICATION FILED APR. 29, 1920.

1,394,782.

Patented Oct. 25, 1921.

UNITED STATES PATENT OFFICE.

GEORGE F. NUTTING, OF SAN FRANCISCO, CALIFORNIA.

OILING SYSTEM FOR ENGINES.

1,394,782.

Specification of Letters Patent. Patented Oct. 25, 1921.

Application filed April 29, 1920. Serial No. 377,494.

To all whom it may concern:

Be it known that I, GEORGE F. NUTTING, a citizen of the United States, and resident of the city and county of San Francisco, State 5 of California, have invented a new and useful Oiling System for Engines, of which the following is a specification.

This invention relates to a lubricating or oiling system for motors and while it is shown as incorporated with an internal combustion engine it is to be understood that the invention is equally applicable to other 10 types of motors and machines to the moving parts of which it is desirable to supply a lubricating medium continuously during the 15 operation of the machine or motor.

Among the various systems that have been adopted for the lubrication of moving parts of machines and especially of the 20 lubrication of an internal combustion engine, one system comprises the arrangement of a distributing member within the casing of the motor so as to convey a portion of a lubricating medium, such as oil, that is 25 centrifugally thrown outwardly by the rotation of the elements of the motor, to the opposite end of the motor casing where it is discharged and permitted to gravitate into suitable pockets or sumps provided in the 30 bottom of the casing. During the operation of the motor certain of its parts are adapted to swing into the pockets or sumps and contact with and splash the oil that may be contained therein. When a motor of this 35 kind utilizing this system of lubrication is installed upon a motor vehicle it is obvious that when the latter is standing or traveling on an inclined plane the oil will drain from the pockets or sumps or take such position 40 that the coördinate moving parts will not contact with and be lubricated by the oil.

It is therefore one of the objects of the present invention to provide an improvement in such type of oiling system as to insure 45 the maintenance of a lubricating medium upon the operating parts irrespective of the angle in which the motor casing may be positioned in ordinary use.

It is a further object of the present invention to improve the distributing means so that the oil that is delivered to the same 50 will be projected in streams or sprays toward and on the given operating parts of the motor so that these parts will be lubri-

cated independently of the presence or absence of lubrication in the pockets or sumps above referred to. 55

A further object of the present invention is to provide means for diverting the centrifugally thrown, moving oil so as to insure 60 an ample supply of the same being delivered to the distributing means; and further to provide for the maintenance of pressure on the oil in the distributing means for the more effective lubrication of the moving 65 parts.

Another object of the invention is to provide a device that is of simple, substantial and inexpensive nature, that can be readily attached to a portion of the motor casing 70 so that the moving oil will be intercepted and directed toward the usual distributing means.

The invention possesses other objects and features of advantage, some of which, with the foregoing, will be made manifest in the following description of the preferred form of the invention which is illustrated in the drawings accompanying and forming part of the specification. It is to be understood 75 that it is not intended to limit the invention to the embodiment shown by the said drawings and description as variations may be adopted within the scope of the invention as set forth in the claims. 80

Referring to the drawings:

Figure 1 is a side elevation of one form of motor with which this present invention is shown as incorporated.

Fig. 2 is a sectional and elevational view 90 in a plane on the line 2—2 of Fig. 1.

Fig. 3 is a plan and sectional view showing the oil deflecting means as applied.

Fig. 4 is a perspective of the attachment.

The invention is illustrated as embodied 95 with a motor having a casing part 2 in which is operative the usual pistons 3 and their valves, the pistons being connected to the usual crank shaft 4 by means of connecting rods 5. The crank shaft and the connecting rods operate across a chamber having 100 a bottom portion 6 that is provided with a plurality of sumps or pockets 7 in which sweep the lower ends of the connecting rods which serve to splash a lubricating medium 105 when the same collects in the pockets and thus serve to lubricate the operating parts so long as there is a lubricant in the sumps.

that may be splashed by the swinging members.

In the type of motor illustrated the crank shaft is provided with a fly-wheel 10 in-
5 closed in a housing or casing part 11 that may be charged with a suitable quantity of lubricating material as oil O and, during the operation of the motor, the rotating fly-
10 wheel 10 dips into the oil O and centrifu-
gally throws the same outwardly to lubricate the associated parts in the housing 11. A portion of the oil that is thus thrown outwardly by centrifugal force and the rotation of the wheel 10 falls into the contiguous re-
15 ceiving mouth 12 of a distributing tube 13 which is extended forwardly through the crank chamber of the motor, the front end of the distributing tube 13 usually being open and freely discharging the oil that falls 20 into the mouth 12, to the bottom of the crank chamber so that it gravitates rearwardly into the sumps 7. It is obvious that if the motor is supported in an inclined position with its axis inclining upwardly toward the
25 front end of the motor the oil in the sumps 7 will tend to drain out or the top surfaces of the oil in the sumps will take such a position with respect to the moving parts, as the lower ends of the connecting rods, that
30 the latter will be ineffective to splash the oil because of failure to contact with the same.

A feature of my present invention is to provide a distributing pipe 13 that is partially closed or has a reduced discharge out-
35 let 14 at its forward end and to provide in the distributing pipe 13 a series of spray orifices 15 in such position that oil collect-
ing in the distributing pipe 13 will be dis-
charged in sprays toward the reciprocating
40 or swinging parts such as the connecting rod 5 and toward the cranks of the crank shaft 4. By restricting the discharge of the oil from the forward end of the pipe 13 it will be seen that the oil will be caused to collect
45 in the pipe and provide for the continuous discharge of sprays through the orifices 15 toward the operating parts.

To increase the efficiency and the reliability of the action of the lubricating system
50 means are provided and so arranged with relation to the fly-wheel 10 that the centrifugally thrown, moving liquid is intercepted and diverted positively toward the mouth or intake portion 12 of the distributing pipe 13. This positive deflection of the oil toward the mouth 12 is secured by means of a barrier that may be formed integrally on the internal surface of the casing 11 surrounding the fly-wheels 10 and parts that
55 60 may be carried thereon, or such deflecting means may comprise a barrier part attachable to motors already constructed and in use.

A form of the diverting means is shown
65 as comprising a barrier having a rearwardly

extending flange 16 perforated at 17 to receive screws by which it may be fastened in a position shown as in Fig. 3 angularly to the line of travel of the moving oil thrown toward the annular portion of the casing 11 70 about the fly-wheel 10. The barrier has a wall portion 18 designed to stand substantially perpendicular to a contiguous surface of the casing section 11 and at the lower part of the wall there is formed a forwardly 75 extending lateral lip 19 spaced sufficiently below or from the casing surface to provide for the passage of the thrown oil toward the wall 18. The oil in moving against the obliquely disposed wall 18 is thus diverted 80 as in the direction of the arrow A, Fig. 3, toward the rearmost end of the barrier which is preferably provided with a funnel or guide 20 so disposed as to discharge the oil into the adjacent mouth 12 of the dis-
85 tributer 13. In the operation of the motor the oil is centrifugally thrown with such force as to form a substantially constant stream through the funnel or guide part 20 of the deflecting means and from the funnel is thrown forcibly across the gap and into the mouth of the distributing pipe 13 in which the oil is maintained at sufficient pressure to cause its discharge in streams from the orifices 15 onto the connecting rods 90 and sweeping cranks of the crank shaft. It will therefore be seen that even though the sweeping parts fail to contact with a lubricating medium in the sumps 7 the swinging parts will be lubricated by jets of oil from 95 the distributing pipe 13.

Ordinarily, during operation of motors using a lubricating system dependent on the oil thrown by centrifugal action of the fly-wheel, when the engine is running slow 105 there is excess oil led by the distributer to the sumps, with a resultant excess to the engine parts. When the engine is running fast the oil is thrown so forcibly that but a small amount falls into the intake of the 110 distributer. By the present invention this is not only remedied, but the amount of oil led to the distributer is proportional to the speed of the wheel that throws it off thus insuring a sufficiency of oil at high speed, 115 without an excess at low speed.

What is claimed is:

1. An oiling attachment for internal combustion engines comprising a distributing pipe having discharge ports at points along 120 its length to discharge onto given portions of the engine, and means for directing a stream of circulating oil into the distributing pipe.
2. An oiling system for internal combustion engines in which oil is centrifugally thrown by a rotary part, including a distributer having an intake disposed adjacent to the said rotary part, and a barrier longitudinally extending angularly in the direc- 125 130

tion of flow and to intercept the thrown oil and project it at pressure due to its momentum into the said intake.

3. An oiling system for internal combustion engines in which oil is centrifugally thrown by a rotary part, including a distributor having an intake disposed adjacent to the said rotary part, and a barrier longitudinally arranged obliquely to the line of 10 movement of and to intercept the moving oil and project it into the said intake.

4. A barrier of L-shaped cross section attachable to the wheel casing of an internal combustion engine to divert oil, which is 15 centrifugally thrown by a wheel in the cas-

ing, toward the intake of a distributing device in the casing, one part of the barrier forming a bottom or gutter to convey the oil.

5. A barrier on the wheel casing of an internal combustion engine to divert oil, 20 which is centrifugally thrown by a wheel in the casing, toward the intake of a distributing device in the casing, and having a bottom flange forming a trough; said flange disposed edgewise to the moving spray or 25 stream of oil.

In testimony whereof, I have hereunto set my hand.

GEORGE F. NUTTING.
